(57) **CLAIM**

The ornamental design for a meat skewer pet treat, as shown and described.

DESCRIPTION

FIG. 1 is a front, bottom and right side perspective view of a first embodiment of a meat skewer pet treat, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front, bottom and right side perspective view of a second embodiment of a meat skewer pet treat, showing my new design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a front, bottom and right side perspective view of a third embodiment of a meat skewer pet treat, showing my new design;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof; and,

FIG. 21 is a bottom plan view thereof.

The evenly-spaced broken lines in FIGS. 15-21 illustrate portions of the meat skewer pet treat that form no part of the claimed design. The dash-dot-dash broken lines in FIGS. 15-21 illustrate the boundary of the claimed design which forms no part thereof.

1 Claim, 21 Drawing Sheets
